(No Model.)

R. B. CAMPBELL & F. E. HOUSE.

FREIGHT CAR.

No. 365,461.

Patented June 28, 1887.

Fig. 1.

UNITED STATES PATENT OFFICE.

ROBERT B. CAMPBELL AND FRANCIS E. HOUSE, OF MARION, IOWA.

FREIGHT-CAR.

SPECIFICATION forming part of Letters Patent No. 365,461, dated June 28, 1887.

Application filed April 26, 1887. Serial No. 236,140. (No model.)

To all whom it may concern:

Be it known that we, ROBERT B. CAMPBELL and FRANCIS E. HOUSE, citizens of the United States, residing at Marion, in the county of 5 Linn and State of Iowa, have invented certain new and useful Improvements in Freight-Cars, of which the following is a specification.

The object of our invention is to so construct a railway-car as to admit of its being readily converted into a stock, grain, or coal car; and the invention consists in the construction and arrangements of parts to this end, as will be hereinafter more fully set forth and claimed.

In the accompanying drawings, forming a 15 part of this specification, Figure 1 represents a side elevation of the car; Fig. 2, a cross-section of the same in the line $y z$; Fig. 3, a fragmentary end view of panels and connective parts, showing the detail of their construction; 20 and Fig. 4, a fragmentary side view of a part of the car next to the door, showing the device for holding the movable panel in position when elevated.

Similar letters of reference indicate corresponding parts.

In the moving of freight it is often quite desirable to be able to use the cars employed in the transportation of stock—for example, in the carrying of coal or merchandise—since 30 there is apt to be a surplus of one sort of cars and a scarcity of another at any point, and especially at certain seasons, when there is a general movement of any one species of freight in one direction. This is particularly true of 35 stock-cars, which for the most part have to be returned empty. The present invention is designed to economize in this matter by providing cars which may be used in one direction for carrying stock or the like and re- 40 turned with a load of coal, or merchandise, or grain, or may carry one species of freight in one end and freight of quite a different character in the other.

It is not claimed that the broad idea of a 45 convertible or combination car is new; but a car which is at once adapted to the requirements of a stock, coal, or grain car we believe to be novel and useful.

The frame of the car A corresponds for the 50 most part with that of an ordinary stock-car. Instead of having the braces B' of the studs B extend to the top, as is common, it is preferred

to let them run but half-way up the studs, as shown, so as to leave the spaces between the studs entirely clear for the easy removal of coal or other freight. The lower half of the side walls is constructed in substantially the same manner as a common stock-car, suitable boards, *a a a a*, being permanently attached to the studding at intervals, as shown. 55

C is a panel corresponding nearly with the size of the open space in the upper half of the side walls each side of the door. This panel is composed of end pieces, *b b'*, and longitudinal slats *c c c c*, corresponding in width to the 60 space between the slats in the lower half of the car. In practice we attach the end pieces on alternate sides of the slats, the one at the door end of the panel projecting outward, so as to leave the interior wall plane at that point, 65 and the one at the corner of the car for convenience projecting inwardly. This panel is mounted on parallel arms *D D' D' D'* of such length and so adjusted as to allow the panel to swing downwardly and match into the 70 lower half of the wall, as shown in the left side of Fig. 1, and upwardly to form a slatted side wall complete, as shown on the other side of said figure.

The construction, position, and operation of 80 the parts are more clearly illustrated in Fig. 2, the pair of arms *D D* being pivoted to the door-post and the pair *D' D'* to the farther end of the car. The panel is held in its elevated position by dogs *d d' d' d'*, which may be 85 weighted for engagement, as shown, or provided with suitable springs for that purpose. The dogs may be still further secured from displacement by means of the latch *e*.

When the panel is thrown down, it is desirable to forcibly draw it into position with respect to the remainder of the wall. The fastening device consists in the pivoted buttons *f*, engaging with the undercut lugs *g g*. A central lever, *f'*, which may serve as one of the 90 fastenings, is connected with the terminal ones by rods or straps *h h* and actuates the whole simultaneously. The lever may be locked by a common hasp, *i*, or like device.

In order to close the entire side wall of the 100 car, we provide another panel, E, which is a continuous piece, as shown, and is hinged in the corner of the car so as to swing up against the ceiling when not in use. A simple but-

ton, *k*, secures it in this position. A similar button, *k'*, may serve to hold it in the other position, as shown in Fig. 2.

To make the walls water-proof, the edges of the slats should be beveled, as shown in Fig. 3, and to admit of the parts being matched a slot is made in the arm *D* at one of its pivotal connections, so that the panel *C* may be raised sufficiently to slip into position at the lower half of the car. Leakage may be still further prevented by providing the joints with weather-strips *l l* of rubber-cloth, leather, or the like.

Having thus described our invention, what we claim as new, and desire to secure by Letters Patent, is—

1. In a freight car, the combination of the side wall having the lower half permanently slatted and the upper half normally open, and a slatted panel mounted on pivotal arms, substantially as specified, and adapted to swing downward and close the interspaces of the lower half of the car or upward to make a uniform slatted side wall, substantially as and for the purposes set forth.

2. In a freight car, the combination of the side wall having its lower half slatted and its upper half open, the slatted panel adapted to match said slatted wall and close its interspaces, and pivotal arms, substantially as described, adapted to support the panel when elevated and to carry it downward to its lower position, substantially as and for the purposes specified.

3. The combination, in a freight car, of the panel *C*, arms *D D'*, and dogs *d d'*, substantially as and for the purpose set forth.

4. In a freight-car, the combination of the slatted side wall, the slatted panel pivotally mounted to swing from the upper half of the car to said slatted lower half, and a device, substantially as described, adapted to lock said panel in the lower position.

5. The combination, in a freight-car, of the side wall having slats on the lower half beveled substantially as shown and described, the panel having slats similarly beveled, and supporting pivotal arms connecting said panel with the wall of the car, and slotted at one or more of its pivotal points, whereby the panel may be raised to slip it into its lower position, substantially as and for the purpose set forth.

6. The combination, in a freight-car, of the slatted side wall, the removable slatted panel, and weather-strips, substantially as and for the purpose specified.

7. In a freight-car, the combination of the side wall having its lower half slatted and its upper half normally open, the pivotally-mounted panel adapted to match said lower portion of the side wall and close its interspaces, and a continuous tight panel pivoted substantially as specified and adapted to close the upper half of the car and to swing up against the ceiling when not in use, substantially as and for the purpose set forth.

In testimony whereof we affix our signatures in the presence of two witnesses.

ROBERT B. CAMPBELL.
FRANCIS E. HOUSE.
